UNITED STATES PATENT OFFICE.

FRANK R. FORD, JR., OF ROSELAND, NEW JERSEY.

RADIATOR ATTACHMENT.

Application filed October 5, 1927. Serial No. 224,099.

My invention relates to attachments for radiators and more especially to radiators of motor cars, aircraft and similar things. The object of my invention is to produce a convenient sight opening in the top front portion of a radiator to the end that one can look into the radiator and see at once the condition of the water, the height of the water, and whether or not the water is circulating properly. My invention is intended to obviate the need of removing the cap of the filling tube of the radiator in the case of excessive heat, and enable the person to look into the radiator and he then can tell by the condition of the water and its circulation or lack of it, whether the heating is due to lack of water, or lack of oil or engine trouble. My invention is also intended to apply this sight glass in a secure, water-tight and convenient manner, to arrange lighting means behind the glass and in the radiator top to facilitate observation and to afford a proper protection for the glass, which can be utilized as an attractive means of advertising the car or displaying the monogram, name or emblem of the owner. These and other advantages will appear more clearly from the description which follows.

Reference is to be had to the accompanying drawings in which similar reference characters represent the corresponding parts in all views.

Figure 1 is a broken front elevation of a radiator showing my improvements.

Figure 2 is a broken vertical section taken through the sight glass and lighting means, and

Figure 3 is a broken plane of the radiator.

In the drawings, 10 represents a conventional radiator which can be of any approved type, and has the customary filling tube 11 and the outer covering shell 12 which is chiefly for ornament and hides the radiator proper.

In the front shell of the radiator near the top and preferably in alignment with the filling tube 11 is a sight glass 13 through which one may look to observe the internal conditions of the radiator. The sight glass has preferably, though not necessarily, a bevelled edge and is held between resilient washers 14 and 15 extending around the edge on the front and rear of the glass, and these and the glass fit in the tubular frame 16 which extends through the shell of the radiator and is expanded at its inner end as shown at 17 so that this will fit opposite the outwardly protrud-

ing part 18 of the shell. A washer 19 is placed between the parts 17 and 18 to make the connection water tight and also afford a resilient support for the tubular frame 16. This frame 60 16 has also preferably a flange 20 acting as an abutment for the washer 15 and sight glass 13 and the outer end of the frame is externally screw-threaded to receive a flanged nut 21 which serves to force the washers and sight 65 glass inwardly and the inner edge of which abuts with the outer end of the shell part 18 when the nut is screwed home.

I preferably protect the glass from external dirt or contact with something which may break or injure it by a door 22 which is carried by the shell or cover portion 12 and has a conventional spring hinge 23 to keep it shut. This door can be ornamented prefer-

ably with some emblem or letter representing the trade mark of the car or perhaps the name of the owner and it is also preferably stencilled so that one can look through the stencil and glass without even opening the door, although to get a full and careful view 80 the door should be opened. This arrangement also has the advantage of lighting up the door so as to make the matter thereon more noticeable. To enable observation to

be quickly and thoroughly made, I preferably 85

arrange a lamp 24 inside the radiator near the top and behind the sight glass 13. This can be an ordinary small electric lamp or bulb and it is protected and kept out of contact with the water in the radiator by a globe 90 25 having a flange 26 which is supported between the resilient washers 27 and 28, thus making a resilient, water-tight support. The lamp can be included in the lighting circuit

of the vehicle to which it is attached, or can 95 be otherwise lighted. The lamp can be conveniently carried by a removable plate 29 which is preferably countersunk somewhat

on the upper side in the middle part and is secured in place by through-bolts 30 extending through the plate 29, the top shell of the radiator 10 and a ring 31. The latter bears against and supports the washer 27 and the bolts have nuts 32 on the inner side by tightening which the globe 25 is securely held in 100 place. Obviously other means for supporting the lamp and attaching a globe around it

can be used without affecting the invention. If it is desired to remove the lamp parts, this can be done by first taking out the sight glass 110 13 and its frame 16, and then one can reach through the opening to the nuts 32.

It will thus be seen that I provide a safe, thoroughly practical, and convenient means of observing the internal conditions of a radiator, and that this means is placed near the top where the height of the water can also be determined at a glance. I have shown a preferred means of making this attachment and providing a light behind the sight glass, but the invention is not limited to the structural details, and I claim broadly the arrangement of a protected sight opening in this particular portion of the radiator.

I claim:

1. A radiator having a sight opening in its front wall, there being a glass mounted in said opening permitting the contents of the radiator to be viewed; a hinged door covering said sight opening, said door having a design stenciled thereon and lighting means 15 behind the sight opening for projecting the

design and for illuminating the interior of the radiator to permit inspection of the same through the stenciled design.

2. A radiator having a sight opening in its front wall, transparent glass mounted in 25 said opening permitting the contents of said radiator to be viewed, a hinged door covering said sight opening, spring means normally closing the door over the sight opening, said door having a design cut thereon and lighting means 30 behind the sight opening for projecting the design and for illuminating the interior of the radiator and permitting inspection of the same through the sight opening.

In testimony whereof, I have signed my name to this specification this 29th day of September, 1927.

FRANK R. FORD, JR.
